His Attorney.

UNITED STATES PATENT OFFICE

107,406

DESIGN FOR A CLOCK CASE

Ivan Bruce, Framingham, Mass., assignor to Warren Telechron Company, a corporation of Maine

Application October 28, 1937, Serial No. 72,472

Term of patent 14 years

To all whom it may concern:

Be it known that I, Ivan Bruce, a citizen of the United States, residing at Framingham, in the county of Middlesex, State of Massachusetts, have invented a new, original, and ornamental Design for a Clock Case, of which the following is a specification, reference being had to the accompanying drawing, forming a part thereof.

The figure is a front perspective view of a clock case showing my new design.

I claim:

The ornamental design for a clock case as shown.

IVAN BRUCE.
